(57) **CLAIM**

The ornamental design for a container with lid, as shown and described.

DESCRIPTION

FIG. 1 is an isometric view of a new design in a first embodiment for a container with a lid; FIG. 2 is an isometric view of a new design in a second embodiment for a container with a lid; FIG. 3 is an isometric view of a new design in a third embodiment for a container with a lid; FIG. 4 is an isometric view of a new design in a fourth embodiment for a container with a lid; and, FIG. 5 is an isometric view of a new design in a fifth embodiment for a container with a lid.

(Continued)

The texture of the container and lid thereof (not the pattern) resembles the texture of concrete.

1 Claim, 5 Drawing Sheets
